OSCILLATION SYSTEM

Nelson P. Case, Great Neck, N. Y., assignor to
Hazeltine Corporation, a corporation of Delaware

Application September 28, 1935, Serial No. 42,602

18 Claims. (Cl. 250—36)

This invention relates to tuned systems and particularly to composite tuned systems or oscillation circuits for oscillators arranged to operate in either of two or more bands of frequencies, such as the local oscillators of multi-band superheterodyne receivers.

A composite tuned system, made up of two or more closed circuits which have one or more common reactance elements, generally has a principal resonant frequency determined by all of the reactance elements of such system and one or more other or spurious resonant frequencies determined by groups of less than all of said reactance elements, such as by the reactance elements in either closed circuit alone. It has been found that under certain circumstances a tuned system of such a character tends to oscillate, and in many cases actually does oscillate, at one of such spurious frequencies when it is desired to have the system oscillate only at its principal resonant frequency. More particularly, it has been found that, when a tunable multi-band superheterodyne receiver is adjusted to receive signals in certain portions of one or more of their signal frequency bands, the local oscillator thereof tends to jump from the frequency at which it is intended to operate to a spurious frequency, thereby effectively preventing reception.

It is an object of this invention to provide a method of, and a means for, preventing spurious oscillations in a composite tuned system of the type described.

It is another object of the invention to provide a tunable multi-band oscillator in which any tendency of the oscillations thereof to jump to a spurious frequency is effectively prevented.

Other objects of the invention will become apparent from a consideration of the following specification, taken in conjunction with the accompanying drawing and the appended claims.

The invention contemplates a composite tuned system made up of two or more component resonant circuits having one or more common reactance elements, the principal resonant frequency being that for the composite tuned system. In order to insure that the composite system oscillates only at such principal frequency, and not at the resonant frequency of one or more of the component circuits, the power factors of such one or more component circuits are modified so that the power factor of each of such component circuits is greater than the power factor of the composite system.

In the drawing, Fig. 1 is a circuit diagram of a tunable multi-band oscillator illustrating the

invention as applied thereto; and Fig. 2 is a circuit diagram, partly schematic, illustrating the invention as embodied in a multi-band superheterodyne receiver.

Referring to Fig. 1, the oscillator there shown comprises a vacuum tube 11, an oscillation system 12 and a feed-back coil 13. The oscillation system 12 comprises two serially-connected inductance elements 14 and 15 across the exterior terminals of which is connected a variable tuning condenser 16. Inductance elements 14 and 15 are individually shunted by two relatively small trimmer condensers 17 and 18, respectively. Inductance element 14 may be effectively short-circuited by a switch 20. Series-connected aligning condensers 22 and 23 are also included in the oscillation system, between a low potential end of inductance element 14 and the grounded terminal of the tuning condenser 16.

Oscillation system 12 is effectively connected across the grid-cathode circuit of tube 11, condenser 24 and resistor 25 being the customary grid condenser and grid leak, respectively. The feed-back coil 13, coupled to the anode of tube 11 by a coupling condenser 26, is inductively related to both inductance elements 14 and 15.

The oscillator with the oscillation system described is tunable over two different frequency bands, operation in the higher frequency band occurring when switch 20 is closed, at which time the oscillator frequency is determined by the resonant frequency of the tuned circuit composed of inductance element 15 and condensers 18, 16 and 23. When switch 20 is opened, as illustrated, the oscillator operates in the lower frequency band, with the oscillation frequency determined by the entire oscillation system comprising inductance elements 14 and 15 and condensers 17, 18, 16, 22 and 23.

In the higher frequency band condensers 18 and 23 serve, respectively, as parallel- and series-aligning condensers, and in the lower frequency band condensers 17 and 22 serve, respectively, as the principal parallel- and series-aligning condensers, in each case in a manner well known in the art. The condenser 23 serves also as an additional coupling or feed-back element between the anode circuit and the oscillation system, as disclosed and broadly claimed in United States Letters Patent No. 2,007,253, granted July 9, 1935, upon the application of William A. MacDonald, and is effective to maintain the amplitude of the oscillations within desired limits over the tuning range of the system. Inductance elements 14 and 15 may be of any suitable value.

Since, however, variable condenser 16 customarily has a fairly wide range of capacity variation, inductance element 14 generally has a substantially greater inductance than inductance element 15 in order that the overlap, if any, of the two bands over which the oscillator is tunable may be small.

It has been found that, when the oscillator is arranged for operation in the lower frequency band (with switch 20 open) and variable condenser 16 is set to a low capacitance so as to tune the oscillator to a frequency in the upper portion of such lower frequency band, the oscillator has a tendency to operate at a frequency determined, not by all the reactance elements then effectively included in the oscillation system 12, but at a frequency determined by only a portion of such elements and in particular at the resonant frequency of the closed circuit including inductance element 14 and condenser 17. This tendency becomes more pronounced as the capacitance of tuning condenser 16 is decreased. When the oscillator changes its frequency of operation from the desired frequency determined by all the inductance elements effectively included in oscillation circuit 12 to the spurious frequency determined by inductance element 14 and condenser 17, this change is effected very suddenly and is commonly known as "jumping".

To overcome this tendency of the oscillator to jump to a spurious frequency, in accordance with this invention, there is provided a resistor 27 in the closed circuit including inductance element 14 and condenser 17, the resistor 27 being so proportioned that the power factor of such closed circuit is greater than that of the complete oscillation system 12, even when the latter is tuned in the upper portion of the lower frequency band. This insures that any oscillation at the spurious frequency is attended with greater expenditure of energy than is oscillation at the desired frequency. As a consequence, the oscillator loses its tendency to oscillate at the spurious frequency.

Preferably resistor 27 is connected, as illustrated, in the capacitative leg of the closed circuit 14, 17. The resistor 27, while thus effectively in series in such closed circuit, is not substantially effective in the oscillation circuit as a whole, particularly in the other portions of the band, inasmuch as, at the frequencies to which the oscillation circuit is tunable, the impedance of the capacitive branch of such closed circuit is appreciably higher than the impedance of the inductive branch thereof. Resistor 27, therefore, serves substantially to increase the power factor of such closed circuit while not substantially increasing the power factor of the oscillation system as a whole.

Fig. 2 illustrates the invention as applied to the local oscillator of a multi-band superheterodyne receiver. In such receiver, an antenna circuit 30 is connected to a radio-frequency selector and amplifier 31 which may be of any suitable type, including a plurality of inductance coils (not shown), selectively connected by a switching mechanism 32, in circuit with a variable tuning device 33 to form a plurality of circuits severally tunable over different bands of signal frequencies. The output of the selector and amplifier 31 is connected through a multi-band coupling system 34 to the signal input circuit of an oscillator-modulator tube 35 provided with an oscillation system 37. In cascade with the oscillator-

modulator 35 are an intermediate-frequency amplifier 40, a detector and automatic amplification control source 41, an audio-frequency amplifier 42, and a sound reproducer 43. The automatic amplification control bias potential may be applied to any one or more of the radio-frequency selector and amplifier 31, the oscillator-modulator 35, and the intermediate-frequency amplifier 40, as desired.

The illustrated multi-band coupling system 34 comprises a primary inductance element 50, three series-connected secondary inductance elements 51, 52 and 53 inductively related to primary element 50, and a variable tuning condenser 54 connected across the exterior terminals of the series-connected inductances 51, 52 and 53, the low potential side of condenser 54 being connected to the low potential terminal of inductance element 51 through coupling and series-aligning condenser 55. Three adjustably fixed trimmer condensers 56, 57 and 58 are connected in parallel with inductance elements 51, 52 and 53, respectively. Inductance elements 51 and 52 may be effectively selectively short-circuited by a switch 60 in a well-known manner. An open-circuited winding 63, connected to the high potential end of primary inductance element 50 and related, principally capacitively, to secondary inductance element 53, is preferably provided to improve the transfer of the coupling system in the highest band of frequencies.

Oscillation system 37 comprises three serially-connected inductance elements 66, 67 and 68 across the exterior terminals of which is effectively connected a variable tuning condenser 70, the low potential terminal of inductance element 66 being connected to the grounded side of tuning condenser 70 through three series-connected condensers 71, 72 and 73. Effectively connected in shunt across the respective inductance elements 66, 67 and 68 are adjustably fixed trimmer condensers 76, 77 and 78, the circuit of condenser 76 being completed through a switch 80 and condensers 72 and 71. Included in the capacitive shunt across inductance element 67 is a resistor 79, serving the same purpose as the resistor 27 of Fig. 1. Switch 80 and a companion switch 81 are arranged to selectively effectively short-circuit inductance element 66 or both inductance elements 66 and 67. Switches 32, 60, 80 and 81 are preferably ganged for unicontrol, as indicated by the dotted lines 82. Likewise, variable condensers 33, 54 and 70 are preferably ganged for unicontrol, as indicated by the dotted lines 84.

Oscillation system 37 is effectively connected across the oscillator grid-cathode circuit of tube 35 through a grid condenser 85 and a grid leak 86, and a cathode biasing resistor 87 and by-pass condenser 88.

The oscillation-producing coupling, or feedback, for oscillation system 37 is provided by a winding 90 connected in the oscillator anode circuit of tube 35 and inductively related to inductance elements 66, 67 and 68, and by the aligning and coupling condensers 72 and 73, the condenser 73 acting alone in the high-frequency range. To assist in maintaining high conversion gain at the high-frequency end of the high-frequency range, the oscillator-modulator is preferably provided with a neutralizing capacitance, illustrated as a turn or two of insulated wire, 93, about the lead to signal input grid of tube 35 and connected to the high potential terminal of condenser 70.

In operation, the desired received signal is selected and amplified in radio-frequency selector and amplifier 31, and further selected and transferred by the coupling system 34 to the oscillator-modulator tube 35, where the signal is converted into a modulated intermediate frequency. The signal, as thus converted, is amplified in the intermediate-frequency amplifier 40, rectified by detector 41, producing the audio frequencies of 10 modulation, which are amplified in the audio-frequency amplifier 42 and reproduced by the sound reproducer 43.

The amplification of the received signal is subject to automatic control by the AVC bias potentials, according to the manner well understood in the art.

When the receiver is adjusted for reception in the middle-frequency range (at which time switches 32, 60, 80 and 81 are in their middle positions) and particularly when the receiver is tuned to desired signals in the high-frequency portion of such range, the oscillation system 31, in the absence of resistor 79, has a tendency to jump from the desired frequency determined by 25 the composite circuit comprising inductance elements 61 and 68 and condensers 71, 78, 70, 73 and 72 to a spurious frequency determined by the component circuit comprising inductance element 67 and condensers 71, 73 and 72. This 30 tendency is effectively minimized or eliminated by the action of resistor 79, which is so proportioned as to insure that the power factor of the component circuit is greater than that of the oscillation system as a whole. This tendency is 35 further minimized over that which would be present if the low potential terminals of condensers 71 and 78 were connected directly to the low potential terminals of inductance elements 67 and 68, respectively, (as illustrated for condensers 17 and 18 in Fig. 1), by connecting the low potential 40 terminals of such condensers directly to ground, as illustrated in Fig. 2, so as to provide a greater effective impedance at the spurious frequency between the oscillator grid and the high potential terminal of the inductance element 61.

When the receiver is adjusted for reception in the low-frequency range, the oscillation system has no tendency to jump from the desired frequency determined by the composite circuit comprising inductance elements 66, 67 and 68 and condensers 76, 71, 78, 70, 73, 72 and 71 to a spurious frequency determined by the component circuit comprising inductance element 66 and condensers 76, 71, 72 and 73. This is principally 55 because inductance element 66 is of relatively large inductance, and thus in practice is a universal wound coil of relatively fine wire, with a resulting relatively high power factor. In contrast, inductance elements 67 and 68 are generally single layer windings of larger wire, so that each has a relatively low power factor.

The methods and means for suppressing spurious oscillations disclosed and claimed herein are not limited to any particular frequency range, 65 nor to oscillators used in superheterodyne receivers. In order to illustrate however, the relative magnitudes of the various circuit elements of a typical circuit arrangement tending toward spurious oscillation and including means for preventing such oscillation, in accordance with this invention, the following approximate values for the oscillation circuit elements, and other pertinent information, are given for a receiver of the 70 type shown in Fig. 2.

	Received signal frequency	Oscillator frequency	
Low-frequency band.....	133-333 kc.	589-789 kc.	5
Middle-frequency band.....	526-1532 kc.	982-1988 kc.	
High-frequency band.....	5.5-18.2 mc.	5.90-18.66 mc.	
Inductance element 68.....	3 microhenries (in air at 1000 cycles)		
Inductance element 67.....	122 Do.		
Inductance element 66.....	630 Do.		
Inductance elements 67 and 68.....	126 Do.		10
Inductance elements 66, 67 and 68.....	785 Do.		
Condensers 77 and 78.....	25 micro-microfarads, maximum, generally adjusted between 3-10 micro-microfarads.		
Condenser 76.....	50 micro-microfarads, maximum, generally adjusted in the vicinity of 40 micro-microfarads.		15
Condenser 70.....	10-453 micro-microfarads, resulting generally in an effective minimum capacitance when connected in circuit, of 40-50 micro-microfarads.		
Condenser 71.....	220 micro-microfarads.		20
Condenser 72.....	500 Do.		
Condenser 73.....	1290 Do.		
Resistor 79.....	100 ohms.		

While I have described what I at present consider the preferred embodiments of my invention, it will be obvious to those skilled in the art that 25 various changes and modifications may be made therein without departing from my invention, and I, therefore, aim in the appended claims to cover all such changes and modifications as fall within the true spirit and scope of my invention. 30

What is claimed is:

1. An electric circuit arrangement for preventing a composite tuned system, composed of a plurality of component tuned circuits having reactance elements individual thereto and a reactance element common with at least two of said circuits, from oscillating at the resonant frequency of one of said component tuned circuits, comprising means substantially increasing the power factor of said one component tuned circuit without substantially increasing the power factor of the composite tuned system. 40

2. An electric circuit arrangement for preventing a tuned system, composed of two serially-connected inductances and at least two condensers, one of which is effectively in shunt with both of said inductances and the other of which is effectively in shunt with only one of said inductances, from oscillating at an undesired frequency determined by said one inductance and its individual shunt condenser, so that instead the tuned system may oscillate at a desired frequency determined by all of said inductances and condensers, comprising means for substantially increasing the power factor of the portion of the tuned system tending to oscillate at the undesired frequency without substantially increasing the power factor of the entire tuned system. 55

3. An electric circuit arrangement for preventing a tunable system, composed of two serially-connected inductances of substantially different value, a variable tuning condenser effectively in shunt with both said inductances and a fixed condenser of relatively small value effectively 65 in shunt with said inductance of larger value, from oscillating when said tuning condenser is adjusted in the vicinity of its minimum value at a frequency determined by said inductance of larger value and said fixed condenser, rather than at the frequencies determined by both said inductances, said tuning condenser and said fixed condenser, comprising means for substantially increasing the power factor for the portion of the system including said inductance of larger 70 75

value and said fixed condenser without substantially increasing the power factor of the entire tunable system.

4. A composite tuned system comprising; a plurality of component tuned circuits having reactance elements individual thereto and a reactance element common with at least two of said circuits; and means for preventing said tuned system from oscillating at a frequency determined by less than all of said reactance elements, comprising means substantially increasing the power factor of at least one of said component tuned circuits without substantially increasing the power factor of the composite tuned system.
5. A tuned system comprising; a plurality of component tuned circuits having reactance elements individual thereto, and also a reactance element common to at least two thereof; and means for preventing said tuned system from oscillating at the resonant frequency of one of said component tuned circuits, comprising resistance means in said one tuned circuit effective to increase the power factor thereof to a value above that for the composite tuned system, said resistance means being so proportioned and disposed with respect to the composite tuned system that said increase in the power factor of said one tuned circuit is effected without substantially increasing the power factor of the composite tuned system.

6. A tuned system comprising; two component tuned circuits having reactance elements individual thereto and a reactance element common thereto; and means for minimizing any tendency of said tuned system to oscillate at the resonant frequency of one of said component circuits rather than at the resonant frequency of the composite system, comprising resistance means effectively included in series in said one component circuit but substantially effectively external to the composite system and of such magnitude as to increase the power factor of said one component circuit to a value greater than the power factor of the composite system.

45 7. A composite tuned system comprising; two serially-connected inductances; a condenser effectively connected across said two serially-connected inductances; a second condenser effectively connected across one of said inductances, said latter inductance and its associated condenser forming a component tuned circuit resonant at an undesired frequency; and means included in said component circuit for increasing the power factor thereof to a value greater than that of said composite tuned system to minimize any tendency of said system to oscillate at said undesired frequency.

8. A composite tuned system comprising; two serially-connected inductances of greatly different values; a condenser of relatively small capacitance effectively connected across said two serially-connected inductances; a second condenser of relatively small capacitance effectively connected across the larger one of said inductances, said latter inductance and its associated condenser forming a component tuned circuit resonant at an undesired frequency; and means in said component tuned circuit for increasing the power factor thereof at said undesired frequency so that said tuned system oscillates primarily at its natural resonant frequency.

9. A composite tuned system comprising; two serially-connected inductances; a condenser effectively connected across said two serially-con-

nected inductances; a second condenser effectively connected across one of said inductances, said one inductance and its associated condenser forming a component tuned circuit resonant at an undesired frequency; and a resistance connected in series in the capacitive leg of said component circuit of such value as to increase the power factor of said component circuit to a value greater than that of the composite tuned system to prevent said system from oscillating at said undesired frequency.

10. A composite tunable system comprising; two serially-connected inductances; a variable condenser effectively connected across said two serially-connected inductances; a fixed condenser effectively connected across one of said inductances, said latter inductance and said fixed condenser forming a component circuit resonant at an undesired frequency; and means included in said component circuit to increase the power factor of said component circuit, at the frequencies corresponding to the settings of said variable condenser in the vicinity of its minimum value, to a value greater than that of said composite system to insure that said system resonates primarily at the desired frequencies determined by said composite system instead of at the undesired frequency determined by said component circuit.

11. A composite system tunable over given bands of frequencies, comprising; a plurality of series-connected inductance elements; a variable tuning condenser therefor; a relatively small fixed condenser effectively in shunt with one of said inductance elements forming a component tuned circuit resonant at an undesired frequency near the upper limit of said band; and means for preventing said system from resonating at said undesired frequency when said system is tuned by said variable condenser in the vicinity of the upper frequency limit of said band without substantially impairing the response of said system when tuned to other portions of said band, comprising resistance means in the capacitance leg of said component tuned circuit proportioned to increase the power factor of said component tuned circuit to a value greater than that of said system when it is tuned in the vicinity of the upper frequency limit of said band.

12. A multi-frequency tuned system comprising; a plurality of reactance elements of one type; a plurality of reactance elements of opposite type; means selectively connecting said reactance elements into different groups of elements to form a plurality of tuned systems having different resonant frequencies, a one of said systems including a component tuned circuit having a natural resonant frequency; and means for attenuating the response of said tuned systems to the resonant frequency of said component tuned circuit without substantially impairing the responses of said tuned systems at their respective resonant frequencies, comprising means substantially increasing the power factor of said component tuned circuit without substantially increasing the power factors of any of said tuned systems.

13. A multi-frequency tunable system comprising; a plurality of inductance elements; a plurality of capacitance elements including a variable tuning condenser; means selectively connecting said elements into different groups of elements to form a plurality of systems tunable over different bands of frequencies, a one of said systems including at least two serially-connected induct-

5
ance elements of which at least one is effectively individually shunted by a capacitance element thereby to form a component tuned circuit having a fixed natural resonant frequency; and means for
5 attenuating the response of said tuned systems to the resonant frequency of said component tuned circuit without substantially impairing the responses of said tunable systems over their several tunable bands, comprising means substantially increasing the power factor of said component tuned circuit without substantially increasing the power factor of any of said tuned systems.

14. A system tunable over either of two bands
15 of frequencies, comprising; two serially-connected inductance elements; a variable tuning condenser effectively in shunt with said serially-connected inductance elements; an aligning condenser effectively connected in shunt with one of
20 said inductance elements; means for selectively effectively removing from circuit said aligning capacitance and the inductance element shunted thereby while leaving the other of said inductance elements in circuit; and means for attenuating
25 the response of said system to the resonant frequency of the portion of said system including said aligning capacitance and the inductance element shunted thereby when in circuit, comprising a resistance included only in such portion of
30 said system.

15. An oscillation generator comprising; a vacuum tube including input and output electrodes; a composite oscillation system connected to an input electrode of said tube comprising at
35 least two component resonant circuits having a common reactance element; a feed-back coupling from an output electrode of said tube to said oscillation system; and means for preventing operation of said oscillation generator at a frequency determined by less than all the reactance elements of said oscillation system, comprising means in at least one component circuit so proportioned and located therein as to increase the power factor thereof to a value above that for
45 said composite oscillation system.

16. An oscillation generator for generating waves of a given frequency comprising; a vacuum tube including input and output electrodes; a composite oscillation circuit connected to an input electrode of said tube including at least two reactance elements of each type and resonant as a whole at said given frequency, at least one of said reactance elements of each type being so proportioned and interconnected as to form a closed circuit resonant at an undesired frequency near said given frequency; a feed-back coupling from an output electrode of said tube to said oscillation system; and means for substantially

impairing the operation of the generator at said undesired frequency without substantially impairing its operation at said given frequency, comprising means for increasing the power factor of said closed circuit to a value greater than that of said oscillation circuit as a whole.
5

17. A tunable oscillation generator comprising; a vacuum tube including input and output electrodes; a tunable oscillation system for said tube connected to an input electrode thereof, said oscillation system including two serially-connected inductances of substantially different value, a variable tuning condenser effectively in shunt with both said inductances, and a fixed condenser of relatively small value effectively in
15 shunt with said inductance of larger value; a feed-back coupling from an output electrode of said tube to said oscillation system; and means, effective when said tuning condenser is adjusted in the vicinity of its minimum value, for preventing said oscillation generator from jumping from an operating frequency determined by all of the reactance elements of said system to a frequency determined by said inductance of larger value and said fixed condenser, comprising means for
20 substantially increasing the power factor of the portion of the oscillation circuit including said inductance of larger value and said fixed condenser to a value greater than the power factor of
25 the entire oscillation system.
30

18. A multi-range oscillation generator, comprising; a vacuum tube including input and output electrodes; an oscillation system for said tube connected to an input electrode thereof, said oscillation system including two series-connected inductances of different orders of magnitude, a variable condenser effectively in shunt with said series-connected inductances for operation over a lower frequency band, a small aligning condenser effectively in shunt with each of said inductances, and means for selectively effectively short-circuiting the inductance of larger magnitude whereby the oscillation generator operates over a higher frequency band; a feed-back coupling from an output electrode of said tube to
40 said oscillation system; and means primarily effective when the oscillation generator is adjusted to oscillate at frequencies in the upper portion of the lower frequency band for preventing the frequency of the oscillations produced by
45 the oscillation generator from jumping away from the resonant frequency determined by all the inductances and capacitances then in circuit to a frequency determined by less than all such inductances and capacitances, comprising resistance means in the circuit of the aligning condenser for said inductance of larger value.
